(57) **CLAIM**

The ornamental design for a table, as shown and described.

DESCRIPTION

FIG. 1 is a front perspective view of a table, showing my new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a bottom plan view thereof;

FIG. 9 is a front perspective view, showing an alternate embodiment of my new design,

FIG. 10 is a rear perspective view thereof;

FIG. 11 is a plan view thereof;

FIG. 12 is a front elevation view thereof;

FIG. 13 is a rear elevational view thereof;

FIG. 14 is a right side elevational view thereof;

FIG. 15 is a left side elevational view thereof; and,

FIG. 16 is a bottom plan view thereof.

The broken lines are for environmental purposes only and form no part of the claimed design.
